CONCRETE MOLDING MACHINE

Norman Bigelow Randall, Tacoma, Wash., assignor to R. C. Draughon and Norman B. Randall, both of Tacoma, Wash., as trustees

Application March 31, 1949, Serial No. 84,663

12 Claims. (Cl. 25—41)

1

This invention relates to apparatus for casting cementitious agglomerates into monolithic structural elements such as pillars, columns and like elongated elements, although it may also be used for casting elements of other shapes if desired.

An object of the invention is to provide novel means for compacting the agglomerates in the mold so as to expel air or gases from the material and in such a way as to counteract the natural tendency of heavier materials, aggregates and particles to settle in the mold.

Another object is to subject the material in the mold to a succession of compressive or squeezing effects from opposite sides the compressive force in each such effect beginning at one end of the mold and travelling progressively toward the other end in a direction opposite to the direction of flow of the material being poured, and opposite to the effect of gravity on said material.

Another object is to combine the aforesaid compacting or squeezing effect with a trowelling effect on opposite sides of the casting so that the principal surfaces of the casting will have a smooth finished appearance.

A further object is to provide a novel mold having movable walls that are compressible for the purposes and in the manner stated above, the mold also being in knockdown form such that it can be removed quickly and easily from the casting after the latter has set or cured and can be reassembled just as quickly and easily for further use.

A still further object is to provide apparatus of the type characterized above having novel means for lifting and removing the poured mold while at the same time holding the movable mold walls in proper molding position.

Additional objects are to provide such an apparatus that is readily adjustable for castings of varying size and shape; that is relatively simple and inexpensive in construction; and that is simple and easy to operate with a minimum of attention and effort.

The drawings show an embodiment of the invention intended particularly for casting monolithic hollow pillars having interlocking edges, but it is to be expressly understood that this embodiment is by way of example only and that the drawings are not to be construed as a definition of the limits of the invention, reference being had to the appended claims for this purpose.

In the drawings,

Fig. 1 is a perspective view of an apparatus embodying the invention;

2

Fig. 2 is a side view of said apparatus;

Fig. 3 is a detail perspective of core supporting means;

Fig. 4 and 5 are detail views of part of a mold lifting means;

Fig. 6 is a sectional detail showing the connection between said lifting means and the mold;

Fig. 7 is a vertical section transverse to the apparatus as shown in Figs. 1 and 2;

Fig. 8 is a perspective showing details of the mold; and

Figs. 9 and 10 illustrate the finished casting and the removal of the mold therefrom.

Referring first to Figs. 1, 2 and 7; the apparatus is mounted on a suitable bed or table 1 supported by a series of piers 2 or the like. Secured to the table 1 are two base plates 3 each of which carries an oscillating jaw as described in detail hereinafter. The mold itself, when in pouring position, is located between the jaws and rests on the inner margins of the plates 3, straddling the dividing space 4 between them so that the positions of the plates may be adjusted to accommodate molds of different sizes.

25 The oscillating jaws are pivoted on horizontal axes parallel and closely adjacent the base plates. 3. In the form shown (Figs. 1 and 7), longitudinal stringers 5 are secured on the upper surfaces of the base plates 3 in any suitable manner, 30 and the jaws 6 are hinged to the upper inner edges of the stringers as shown at 7. The upper surfaces of the stringers are inclined outwardly and downwardly as shown; and the jaws are capable of oscillating about their hinges 7 from the upright full line positions to the tilted dotted line positions shown in Fig. 7.

The configuration and structure of the mold itself will of course depend upon the shape of the casting to be made, and the drawings illustrate 40 a mold for casting an elongated pillar or column having a hollow core and interlocking top and bottom edges as shown in Figs. 7, 9 and 10. This mold comprises a pallet 8 resting on the plates 3 (Fig. 7) and having flanged side edges 9 and a longitudinal tapered ridge 10 along its center line. Mold inserts 11 are placed in the pallet, one on each side of the central ridge 10 and between it and the side flange 9. These inserts are provided 45 with longitudinal outer grooves 12 and ridges 13 so as to shape the bottom edge of the casting into the female part of a tongue and groove type connection to an adjacent casting.

The sides of the mold are formed by sheet metal plates 14, the lower edges of which are inserted between the side flanges 9 of the pallet and

the mold inserts 11. In the case of the pillar shown in the drawings, these side mold members extend vertically upward when in correct molding position to form flat parallel outer surfaces of the casting. At the top of the casting, the side mold members are bent inwardly at 15 and then shaped to provide inner longitudinal ridges 16 and grooves 17 so as to provide a tongue forming the male part of an interlocking connection with an adjacent casting having the configuration produced by the mold inserts 11.

The hollow core of the casting is formed by a sheet metal tubular casing 18 which is slit longitudinally as shown at 19 and rolled to a diameter slightly less than that desired for the opening in the casting so that the slit edges normally overlap somewhat. This core casing is supported in molding position by mandrels 20 mounted movably on the table 1 and adapted to enter the open ends of the core casing. In the form shown, laterally spaced parallel rails 21 are secured to the lower side of the table 1 and grooved guide rails 22 are secured to their inner sides. The mandrels 20 are carried by slides 23 movable between the rails 21 and having supporting and guiding ribs 24 which slide in the grooved guide rails 22. The outer ends of the slides 23 carry blocks 25 to which the outer ends of the mandrels 20 are secured above the table 1, the ends of the table being slotted to permit the movement of the blocks 25 that is required to move the mandrels 20 into and out of the ends of the core casing. Any suitable means can be employed to effect such movement. As shown, the lower sides of the slides 23 carry racks 26 each of which is driven by a pinion 27, reduction gearing 28 and an electric motor 29.

The slit edges of the core casing 18 will normally overlap slightly as stated above, and the mandrels 20 are tapered slightly so that when they are inserted into the core casing, the latter is expanded to the desired size. When thus expanded, an opening formed in the slit edges of the core casing at the approximate center of the machine engages over a similarly shaped keeper post 30 mounted on the central ridge 10 of the pallet. This keeper holds the core casing in its expanded condition after the core mandrels 20 are withdrawn therefrom and while the casting is being cured as hereinafter described. After curing, however, and when the pallet is dropped from the casting as shown in Fig. 10, the keeper 30 is withdrawn and the slit edges of the core casing may then be overlapped to decrease its size and facilitate its removal from the casting. The inner surface of the core casing may be provided near its ends with suitable hooks 31 (Fig. 7) for use in twisting the casing to overlap its edges and in withdrawing the casing from the casting, and in this case the sides of the core mandrels 20 are grooved as indicated at 32 to slide over the hooks 31.

The ends of the mold are completed by suitable plates which cooperate with the pallet 8 and side walls 14 and are arranged to permit the mandrels 20 to move slidably through them. In the form shown, vertical end plates 33 (Fig. 1) are detachably connected to the pallet by means of studs 34 extending outwardly from the opposite ends of the central ridge 10 of the pallet and through openings in the end plates 33, the end plates being held on the studs by means of suitable cotters 35. The width of these end plates is sufficient to close the ends of the molds, taking into account the hereinafter described

oscillation of the side mold members 14, and hence they extend substantially beyond the side walls when the latter are in their vertical molding positions. However, the end plates 33 may be cut back to less width at the level of the inwardly bent horizontal portions 15 of the side mold members, and these portions may be provided with outwardly extending lugs 36 bent over the cut-back edges of the end plates to restrain them against endwise displacement but slidably along said edges to permit lateral oscillation of the side mold members. The end plates 33 are provided with circular openings registering with the ends of the core casing 18 to permit the movement of the mandrels 20. Also the circumferences of these openings may be interrupted by one or more projections or lugs extending into the openings and slidably engaging in corresponding grooves in the mandrels. Fig. 1 shows one such lug 37 at the bottom of the opening in the end plate 33, this lug engaging in a groove 38 in the lower side of the mandrel 20. The grooves 38 may also engage over the top of the keeper 30 when fully inserted into the core casing. The groove 38 also prevents vacuum effects which might interfere with withdrawal of the core supports.

The side walls 14 of the mold are flexible about their lower edges, which are held between the pallet flanges 9 and mold inserts 11, so that each side wall may oscillate as a unit with its associated jaw 6. For this purpose the upper edges of the flexible side walls are detachably connected with the jaws by means of channel-shaped cover plates 39 placed on top of the jaws with their depending flanges over the top edges of the side mold members 14 as shown in Fig. 7. Hence when the plates 39 are in place, the side mold members and the jaws are connected for oscillation together about the jaw hinges 7. The use of the plates 39 for this purpose has the advantage of protecting the jaws from overflow of the agglomerate which is poured into the open top of the mold between the inner flanges of the cover plates. Preferably the sides of the jaws 6 are shaped to conform to the configuration of the side mold members 14 over the greater part of their area so as to provide a firm support for the sides of the mold during oscillation and particularly in the molding position shown in Fig. 7.

The mold can be poured in any suitable manner. For example, a suitable hopper 40 (Fig. 1) is filled with a measured quantity of agglomerate, and when the mold has been assembled in the position shown in Fig. 7, the hopper is moved over the mold and its contents discharged into the open top of the mold, the hopper being thereafter moved back out of the way.

The jaws 6 and side mold walls 14 are oscillated during pouring of the mold and for a desired period thereafter until the mold is ready to be removed and cured. Preferably this oscillation is effected by a suitable number of toggle mechanisms distributed along each jaw, two such mechanisms for each jaw being shown in the drawings. Brackets 41 are secured to the outer sides of the jaws, and toggle links 42 are pivoted thereto at 43, the other ends of these links are pivotally connected at 44 to toggle links 45, the other ends of which are pivoted at 46 to the upper ends of levers 47 normally standing in the upright position shown in Fig. 7. Toggle operating arms 48 are connected to the toggle pivots 44 at one end, their other ends being pinned at 49 to eccentrics 50 rotating with shafts 51. These toggle mech-

anisms are duplicated for the two jaws and the two shafts 51 on opposite sides of the machine are driven in synchronism in any suitable manner. As shown, a common electric motor 52 (Fig. 2) and its worm wheel 53 drive a worm wheel 54 on a central shaft 55. Sprockets 56 on the shaft 55, chains 57, and sprockets 58 on the shafts 51, serve to drive these shafts 51 in synchronism and in opposite directions.

In the operation of the toggle mechanism described above, the eccentric 50 cause vertical reciprocation of the toggle operating rods 48 so that the toggle joints 44 are moved alternately above and below their neutral positions shown in the drawings, shortening the toggles and oscillating the jaws 6 and side mold members 14 about the hinges 7. It will be observed that the direction of flow of the material discharged from the hopper 40, plus the force of gravity, tends to cause the agglomerate to flow downwardly around the sides of the core casing 18 and into the bottom of the mold. This motion of the material is to a certain extent opposed by the effect of the oscillating side mold members 14 which, after being withdrawn outwardly, exert a squeezing or compressing effect on the material as they are swung inwardly again, the compression beginning at the bottom of the mold and moving progressively upward. Thus the tendency is to squeeze the material upwardly in the mold in opposition to its downward flow and to the effect of gravity. This repeated squeezing or compression combined with vibration tends to maintain a homogeneous consistency throughout the mold material and to prevent settling of heavy aggregates, composites or particles. At the same time the material is compacted to increase its density and air or gases are expelled from the mold. Also the principal surfaces of the casting which in this case include only its two sides are smoothed to provide a smooth finished appearance.

When the molding operation has been completed, the covers 39 are removed to disconnect the jaws 6 from the side mold members 14 and the jaws are then swung outwardly to the dotted line position shown in Fig. 7 so that the mold can be lifted out of the jaws (the mandrels 20 of course being withdrawn from the core casing). In the form shown, this lateral withdrawal of the jaws is accomplished by swinging the upright levers 47 about pivots 59 on suitable brackets secured to the table 1. The lower ends of the levers are pivotally connected at 60 to links 61, the other ends of which are pivoted at 62 to the arms 63 of a bell crank lever mounted loosely on the central shaft 55 as described above. An operating handle 64 is rigid with the hub of the bell crank lever and extends outwardly to one side of the machine. When this lever is depressed, the bell crank is rotated to pull the lower ends of both levers 47 inward simultaneously and thus to withdraw the jaws 6 to their dotted line positions. The levers 47 on the same side of the machine can be connected for simultaneous operation by the handle 64, as for example by means of rods 65.

Before the jaws are so withdrawn, however, the flexible side mold walls 14 are suitably braced or supported so that they will not bulge or distort when no longer supported by the jaws and during lifting and handling. Preferably this is accomplished by the mold lifting means which, as shown in Fig. 2, comprises a plate 66 having vertical legs 67 depending from its sides and

adapted to embrace or straddle the mold and thus hold the side mold members 14 in molding position. To accommodate the legs 67 when the lifter is lowered onto the mold, the inner sides of the jaws 6 are recessed or slotted at 68, each slot being of the proper size and shape to receive one of the legs. After the covers 39 are removed, and while the flexible side walls are still supported in molding position by the jaws, the lifter 66 is lowered to insert the legs 67 in the slots 68 between the jaws and the side mold walls, after which the jaws are withdrawn laterally as described above.

Preferably the lower ends of the legs and the pallet 8 are provided with cooperating engageable connections for lifting the mold and casting from the jaws. As shown in Figs. 4 and 5, the lower ends of certain of the legs are recessed and hook members 69 are pivoted at 70 in the recesses. The hooks 69 can be swung about their pivots by rods 71 which slide in grooves in the legs 67 and project above the top of the lifter 66 where pairs of opposite rods 71 are preferably connected for simultaneous operation by cross bars 72. Cover plates 73 enclose the rods 71 and hooks 69.

The pallet is provided with lugs which are arranged to be engaged by the hooks 69 on operation of the rods 71. Rails 74 extend along and are suitably secured to the side edges of the flanges 9 of the pallet, these rails being recessed at 75 to receive the hooks 69 and being provided with lugs 76 to be engaged when the hooks are operated by the rods 71. Preferably the rails 74 extend above the top edges of the flanges 9, and the lower ends of the legs 67 are notched so as to provide depending feet 77 of reduced thickness which fit between the rails 74 and the side mold members 14 as shown in Fig. 6. In this way the lifter is securely connected to the pallet to lift the entire mold as a unit from the jaws, and at the same time the legs 67 are held by the rails 74 so as to brace and support the flexible side mold members 14 and hold them in correct molding position while the mold is being lifted and transported to another place for curing. During curing, the lifter may be left in position to brace the sides of the mold, or the mold may be lowered into a suitable form and the lifter removed.

When the casting has been cured, the end plates 33 are removed and the casting lifted in any suitable manner. The pallet 9 is then free to drop from the bottom of the casing as indicated in Fig. 10 since there is no contact or adhesion between it and the casting itself. The side mold members 14 can easily be removed either before or after dropping the pallet by bending them outwardly to break them away from the sides of the casting as shown in Fig. 9. Once the pallet has been removed, the mold inserts 11 may also be loosened and removed, and the keeper 39 being withdrawn from the core casing 18, the latter can be extracted by means of the hooks 31. The completed casting is then ready for sale and use. The mold parts are then cleaned if necessary and reassembled for use in making another casting.

It will be understood that in some cases the side walls 14 can be omitted, the faces of the jaw members being made continuous (by omitting the recesses 68) and compressing and shaping the mold material by direct contact therewith. In such cases the casting is allowed to set up sufficiently while still in molding position to permit removal and handling by the lifter without the support of the side mold walls, taking into account the fact that the lifter itself may provide

very considerable lateral support for the casting if its legs are not too widely spaced.

While only one embodiment of the invention has been described with particularity and illustrated in the drawings, it will be understood that the invention is not restricted to this embodiment but is susceptible of a variety of mechanical expressions, and also that various changes can be made in the form, details of construction, and arrangement of the parts, all without departing from the spirit of the invention. Reference should therefore be had to the appended claims for a definition of the limits of the invention.

What is claimed is:

1. Apparatus of the class described comprising a pallet, end mold members connected to the ends of the pallet, side mold members extending between said end mold members and having their lower edges connected to the sides of the pallet, the portions of said side members above their lower edges being oscillatable toward and away from each other, oscillating side supports engaging and oscillating said side mold members, said side supports being withdrawable laterally whereby the pallet and side and end mold members may be removed from the apparatus.

2. Apparatus of the class described comprising a pallet, end mold members connected to the ends of the pallet, side mold members extending between said end mold members and having their lower edges connected to the sides of the pallet, said side mold members being bendable about said lower edges, oscillating means engaging and bending said side mold members to oscillate them toward and away from each other, said oscillating means being withdrawable laterally whereby the pallet and side and end mold members may be removed from the apparatus.

3. Apparatus of the class described comprising a pair of spaced jaws oscillatable toward and away from one another on horizontal axes, a mold located between the jaws and comprising a pallet, end mold members connected thereto, and side mold members extending between said end mold members and having their lower edges connected to said pallet, the portions of said side mold members above said lower edges being oscillatable toward and away from each other, and means detachably connecting said side mold members and said jaws for oscillating movement together, said jaws when detached from said side mold members being laterally withdrawable whereby said mold can be removed from between the jaws.

4. Apparatus as claimed in claim 3, said side mold members being flexible for oscillation by said jaws.

5. Apparatus of the class described comprising a pair of spaced jaws oscillatable toward and away from one another on horizontal axes, a mold located between the jaws and comprising a pallet, upright end walls connected to the ends of said pallet, and upright flexible side walls extending between said end walls and having their lower edges connected to the sides of said pallet, the upper portions of said side walls being oscillatable toward and away from each other about said lower edges, a hollow core extending between said end walls, core supporting means movable into and out of the ends of said

core through openings in said end walls, and means detachably connecting each side wall to one of said jaws for oscillation therewith, said jaws when detached being laterally withdrawable whereby said mold can be removed from between the jaws.

6. Apparatus as defined in claim 5, the faces of said jaws being shaped to conform to and engaging said side walls over the greater part of their area to support the sides of the mold.

7. Apparatus of the class described comprising a mold having a bottom pallet, upright end walls connected thereto, upright side walls having their lower edges connected to said pallet and bendable about said lower edges for oscillation toward and away from each other between said end walls, and oscillatable means engaging said side walls for supporting and oscillating said side walls while the mold is being poured.

8. Apparatus as defined in claim 7, the upper end portions of said side walls engaging and retaining the upper portions of said end walls against endwise displacement but being slidably laterally relative to said end walls during oscillation of said side walls.

9. Apparatus as defined in claim 7, said pallet having flanged side edges, and mold inserts located in the bottom of the mold between said flanged side edges, the lower edges of said side walls being engaged between said mold inserts and said flanged side edges of the pallet.

10. Apparatus of the class described comprising a mold pallet, upright end mold walls connected to said pallet, side mold members extending upwardly at the sides of said pallet and oscillatable between said end walls about their lower horizontal edges, and oscillating means engaging said side members and moving them alternately away from each other and then back toward one another to molding position.

11. Apparatus as defined in claim 10, said oscillating means comprising toggle means each having links pivoted end to end to form a toggle joint and a toggle operating member pivotally connected to the toggle joint, the outer end of one link pivotally engaging one of said side members and the outer end of the other link having a normally stationary pivot.

12. Apparatus as defined in claim 11, said outer end of said other link being pivoted on a normally stationary lever, and means for swinging said lever whereby the toggle links pull the side mold member outwardly beyond its range of oscillation.
